RADIO RECEIVING APPARATUS

Application filed May 6, 1926. Serial No. 107,015.

This invention relates to radio receiving apparatus, and more particularly to apparatus of this kind having vacuum tube amplification.

Generally stated, the object of the invention is to improve the receiving efficiency of a radio receiving set of the kind shown and described and covered broadly in prior application No. 754,501, filed December 8, 1924, in which a Wheatstone bridge arrangement is involved for preventing so-called oscillation in radio frequency amplifier circuits of this general type, and to thereby insure against any interference of this kind with the proper reception of the incoming signal.

A special object, with a view to improving the receiving qualities of the receiving set, and the amplification and other desired results, is to provide a novel and improved circuit arrangement whereby a continuous metallic path or circuit connection is provided from the filament of the vacuum tube through the secondary of the transformer or repeating coil, and then through inductance to the filament of the lamp or vacuum tube, to insure the desired improvement in the operation of the receiving set, as will hereinafter more fully appear.

To the foregoing and other useful ends, the invention consists in the matters herein-after set forth and claimed, and shown in the accompanying drawings, in which,

Fig. 1 is a diagram of a radio receiving apparatus involving the principles of the invention.

Fig. 2 is a simplified diagram, using the ordinary Wheatstone bridge arrangement to illustrate the invention, thus showing the theory and the mode of operation of the invention.

As thus illustrated, the invention comprises an aerial 1 which leads to ground 2 through the ordinary primary 3 of the repeating coil or transformer. The secondary 45 coil 4 of said transformer has one terminal connected to the grid 5 of the first vacuum tube, and the filament 6 of said tube is connected through the variable condenser 7 with the other terminal of said secondary coil.

50 The condenser 7 is connected in series with a

similar condenser 8, which latter is connected at one side to the upper terminal of the coil 4 and, therefore, to the filament of the tube. The middle point of the connection between the two condensers is connected to the filament 55 as shown. The condenser 7 and the lower terminal of the coil 4 are connected through the stopping condenser 9 to one terminal of the primary 10 of the next repeating coil or transformer, and this same terminal of this 60 primary coil 10 is connected to the plate 11 of said vacuum tube, substantially as shown in the diagrams. The upper terminal of the inductance coil 12 is connected to the connection between the filament and the middle 65 point of the connection between the two condensers 7 and 8, as is also the variable condenser 13, while the lower terminal of the coil 12 is connected to the connection between the condenser 9 and the lower terminal of the 70 coil 4, as shown, and, again, the condenser 13 is similarly connected, whereby the coil 12 and the condenser 13 are connected in multiple and in shunt of the condenser 7 previously mentioned.

In this way, and looking at Fig. 2, which latter is laid out in the form of a Wheatstone bridge, it will be seen that this bridge comprises the usual four arms connected between the points 14, 15, 16 and 17, these points being 80 the junctions between the arms of the Wheatstone bridge arrangement thus formed. In this way, the previously mentioned condenser 7 is in the arm between the points 14 and 17, while the condenser 8 is in the arm between the points 14 and 15, so that each of these two arms has adjustable capacity therein; and the previously mentioned condenser 9 is in the arm between the points 16 and 17; while the grid to plate capacity, ordinarily 85 existing in any vacuum tube, is in the arm of the bridge connected between the points 15 and 16, as shown. Consequently, the condenser 13 and the coil 12, as shown in Fig. 2, are connected in multiple and are in shunt of the 90 condenser 7, which latter forms one of the capacities of the Wheatstone bridge arrangement. The coil or winding 4 previously mentioned is connected between the points 15 and 17, as shown in Fig. 2, while the coil 95 100

or winding 10 previously mentioned is connected through battery and between the points 14 and 16 of the Wheatstone bridge arrangement.

5 In this way, therefore, it will be seen that an unbroken metallic path can be traced from the grid 5 around through the coil 4, and then through the inductance 12 to the filament 6, whereby the grid to filament capacity, if 10 any, is in the metallic circuit including the coils 4 and 12 of the circuit arrangement shown and described, this grid to filament capacity being indicated in dotted lines in Fig. 2 of the drawings, and beneficial effects 15 will result from this combination and circuit arrangement, in the operation of the receiving set.

The principal advantage to be obtained, in the use of the radio frequency choke coil 12, 20 is to remedy the difficulty which is often encountered when a radio receiving set is employed in close proximity to, or in the neighborhood of, an electric power plant where the current is frequently turned on and off, as 25 in the operation of elevators. In such case, the receiving set is liable to be affected, as a direct current charge is liable to be put on the grid of the vacuum tube, and this will momentarily render the vacuum tube inoperative 30 for the receiving of signals. This is liable to happen, with the Wheatstone bridge arrangement shown and described, and hence the addition of the coil 12, in combination with the Wheatstone bridge arrangement, is found to be desirable and helpful 35 in situations of the kind described. The coil 12 will permit the passage of direct current charges, so that they can gradually leak off, but this coil will not permit passage 40 therethrough of the radio signal currents. The same arrangement is shown, it will be seen, for the second stage of amplification, in Fig. 1 of the drawings, and it will be understood that the coil 12 can be used in combination 45 with each and every vacuum tube or step of amplification, in any receiving set where the Wheatstone bridge arrangement shown and described is employed, or in any receiving set circuit in which capacity is interposed in the path between the grid and the filament, so that without the coil no metallic path will exist between the grid and the filament. Also, of course, the coil 12 could be connected directly across from the 50 terminal of the grid to the terminal of the filament and produce good results, but in practice it is found preferable to include the secondary 4 in series with the coil 12, in the metallic path between the grid and the filament.

Without disclaiming anything, and without prejudice to any novelty disclosed, what I claim as my invention is:

1. A radio receiving apparatus comprising 65 a vacuum tube having a filament and a grid

and a plate, elements forming in effect a Wheatstone bridge arrangement with substantially pure capacity only forming each arm of said bridge, the secondary of a repeating coil being connected between opposite junctions of said bridge, one such capacity being formed by the grid to plate capacity of said tube, to thereby suppress oscillation of the tube, and instrumentalities forming an unbroken metallic path through the secondary with inductance therein between the grid and the filament of said vacuum tube, said inductance permitting the passage of direct current charges but preventing the passage of radio signals. 70 75 80

2. Radio receiving apparatus as set forth in claim 1, said instrumentalities comprising said inductance in shunt of one arm of said Wheatstone bridge arrangement.

3. Radio receiving apparatus as set forth in 85 claim 1, said instrumentalities comprising said inductance in shunt of one arm of said Wheatstone bridge arrangement, and variable capacity connected in multiple with said inductance. 90

4. Radio receiving apparatus as specified in claim 1, the capacity in two of said arms being adjustable for tuning the bridge to resonance.

5. Radio receiving apparatus as specified 95 in claim 1, comprising means for tuning said bridge to resonance.

6. In radio receiving apparatus, the combination of a vacuum tube having a grid and a plate and a filament, a repeating coil having 100 a secondary, instrumentalities forming with said secondary an unbroken metallic path having inductance therein between said grid and said filament, and means for tuning the apparatus to resonance, said inductance permitting the passage of direct current but preventing the passage of radio signals. 105

7. Radio receiving apparatus as specified in claim 6, said instrumentalities comprising inductance connected between one terminal of said filament and one terminal of said secondary. 110

8. Radio receiving apparatus as specified in claim 6, said instrumentalities comprising inductance and adjustable capacity in multiple therewith. 115

Specification signed this 24th day of April, 1926.
